TAPE DISPENSING DEVICE

Daniel M. Ganz, Baldwin, N. Y.

Application June 12, 1957, Serial No. 665,162

5 Claims. (Cl. 206—59)

The present invention relates generally to an improved ribbon and/or tape dispenser, and in particular to an improved means for cutting tape or ribbon as it is dispensed from a roll.

Many individuals and commercial users are faced with the problem of measuring and cutting ribbon and/or tape for gift wrapping and the like. The present practice is to dispense, by pulling off, the required amount of tape or ribbon from its spool or holder and then in a second separate operation, to cut the ribbon with a scissors, knife or like cutting instrument.

Broadly, it is an object of the present invention to provide an improved dispenser which will both be suitable for dispensing the ribbon or tape and at the same time will serve as a cutter thereby enabling the user to cut a measured length of ribbon or tape in a single operation.

It is a further object of the present invention to provide an improved means for association with a tape dispenser which enables the cutting of a prescribed length of tape pulled from the dispenser and the simultaneous clamping of the roll of tape during the cutting operation.

Conventional dispensers usually comprise an inner drum around which the tape or ribbon is wrapped or spooled. This inner drum for the roll of tape or ribbon is mounted in such a way as to allow the tape or ribbon to be unspooled or unwound when the user wishes to dispense a desired length of tape or ribbon.

In accordance with the present invention a combined cutting and locking member is mounted on the tape dispenser in operative relation to the roll of tape or ribbon so that it may serve both for the cutting off of a prescribed length of tape and the simultaneous locking of the roll of tape against rotation during the cutting operation. The combined cutting and locking member is rockably mounted by coaxial pivots on the dispenser body whereby as one end, provided with cutting means, is elevated relative to the body, the other end, provided with locking means, is depressed into contact with the periphery of the roll to effectively lock the same against rotation. Thus by a simple manual manipulation, the user may dispense and cut off a prescribed length of ribbon-like material. The simplicity of the construction facilitates its use on the type of dispensers which are disposed of after the ribbon or tape carried thereby is exhausted.

The above brief description as well as further objects, features and advantages of the present invention will be more fully appreciated by reference to the following detailed description of presently preferred but illustrative embodiments, when taken in conjunction with the accompanying drawings, wherein:

Fig. 1 is an exploded perspective view showing the various components of a tape dispenser in accordance with the present invention before said components have been assembled;

Fig. 2 is a perspective view showing the tape dispenser in the hands of a user and in position for the cut-off of a prescribed length of tape;

2

Fig. 3 is a side elevational view, with parts broken away and sectioned, showing the relationship of the pivoted cutting and locking member relative to the roll of tape or ribbon and illustrating in broken lines the position of said member during the cutting operation;

Fig. 4 is an elevational view taken from the right of Fig. 3; and,

Fig. 5 is a side elevational view, with parts sectioned, showing a tape dispenser embodying a modified combined cutting and locking member.

Referring now specifically to the drawings, there is shown in Figs. 1 to 4 inclusive an improved tape dispenser in accordance with the present invention, generally designated by the reference numeral 10, which is adapted to dispense selected cut lengths of ribbon-like material from a roll 12 of said material. The tape dispenser 10 includes a two-part dispenser body 14 which includes parts 16, 18, and a combined tape cutting and locking member 20 which is rockably mounted on the dispenser body 14. The dispenser body 14 is composed of the identical parts or sections 16, 18, each of which includes a generally circular outer wall 16a, 18a and an inwardly projecting hub 16b, 18b. The inner faces of the hubs 16b, 18b are adapted to abut and confront each other and together make up an axle or rotatable mount for the roll of tape 12. The parts or sections 16, 18 of the body 14 are connected together, in this illustrative form of the invention, by a rivet or stud 22 having a head at one end 22a and adapted to be peened over at its other end as 30 at 22b (see Fig. 2) for securing the parts 16, 18 together and in assembly with the roll 12.

The combined locking and cutting member 20, in this illustrative form of the invention, is of a one-piece metal stamping and incorporates oppositely directed ears or trunnions 20a, 20b which are adapted to serve as coaxial pivots for the member 20 to mount the same for rocking movement about the trunnions 20a, 20b as a transverse median pivot. The trunnions 20a, 20b are received in respective apertures 24, 26 formed in the outer or end 40 walls 16a, 18a of the dispenser body parts 16, 18 adjacent to and spaced inwardly from the outer peripheries of said walls. The assembly of the combined locking and cutting member 20 with the dispenser body 14 may be achieved simultaneous with the assembly of the two body parts 16, 18 by insertion of the respective trunnions in the associated holes and the bending over of the portions of the trunnions which project outwardly of the walls, for example as illustrated at 28 in Fig. 2. These trunnions serve to reclude relative movement between the sections 16, 18 of the body 14.

At one end of the member 20 there is provided a cutting or knife edge 30 which is seen to extend at right angles to the walls 18a, 16a whereby the cut will extend transverse of the tape 12. Alternatively, if a bias cut is desired across the tape, the cutting edge 30 can be disposed at an appropriate angle with respect to the walls 16a, 18a.

Adjacent the other end of the member 20 and at the side remote from the cutting knife or edge 30, there is 50 formed a brake section or pressure foot 32 which is adapted to contact the outer periphery 12a of the roll 12 to exert a brake effect on the roll during the cutting operation. If desired the undersurface of the pressure foot or brake section 32 may be formed with downwardly extending integral projections 34 serving to enhance the gripping action of the foot 32 on the outer periphery 12a of the roll 12. Other similar means which increase the frictional contact between the foot 32 and the outer periphery 12a may be applied to the member 60 20, either as an integral part thereof or as an attachment thereto. For example, a rubber coating may be formed on the undersurface of the foot 32 to engage the roll.

A typical sequence of operations will now be described in detail to facilitate a more thorough understanding of the present invention:

The user grasps the dispenser body 14, as illustrated in Fig. 2, with one hand and with the other hand pulls off a prescribed section of the tape, generally designated by the letter T. Thereupon the user pulls upwardly on the length T to be cut off, as illustrated by the directional arrows and the dotted line showings in Fig. 3, to bring the tape against the knife or cutting edge 30. The pressure of the tape bearing against the knife or cutting edge 30 will tend to rotate or rock the member 20 in one direction about its coaxial pivots 20a, 20b into a clamping position (illustrated by the broken lines in Fig. 3) wherein in the foot or brake section 32 bears against the outer periphery 12a of the roll 12 in which clamping position the member 20 is locked against further rocking movement in said one direction. At that time the cutting edge 30 will be spaced from the periphery of the roll 12 and the continued exertion of pressure against the cutting edge 30 will cause the required severance of the tape.

When the cutting action is complete, the user can grasp the newly cut end of the roll of tape and pull the same to dispense a further length. Since no pressure will be exerted against the cutting edge 30 the foot 30 is free to move away from the periphery of the roll 12 thereby enabling the dispensing of a further length of tape.

In the further embodiment illustrated in Fig. 5, the details of the dispenser body are identical and accordingly the same has been designated by the reference numeral 14'. In this embodiment the locking member 20' is of modified construction, but includes pivots 20a', 20b' intermediate its end and the cutting edge 30' at one end thereof. In lieu of the means for clamping the roll 12' during the cutting operation employed in the main embodiment, the modified locking member 20' is formed with a downwardly-extending pressure foot or brake section 32' at the end remote from the knife edge 30' which is brought to bear against the surface 12a' of the roll in response to the pivotal movement of the member 20' under the directive force of the tape being pulled from the roll.

A latitude of modification, change and substitution is intended in the foregoing illustrative embodiments and in some instances some features of the invention will be used without a corresponding use of other features.

What I claim is:

1. In combination, a dispenser body including spaced coextensive walls, a roll of ribbon-like material disposed intermediate said walls and journaled on said dispenser body to enable a user to pull successive lengths of said ribbon-like material from said roll, and a combined cutting and locking member disposed between said walls in spaced confronting relation to the outer periphery of said roll, coaxial pivots on said cutting and locking member intermediate the ends thereof mounting same for rocking movement whereby one end of said member is elevated as the other end of said member is depressed, a cutter formed on said one end of said member and engageable by said ribbon-like material as the latter is pulled from said roll, engagement of said ribbon-like material being effective to rock said other end of said member into contact with the outer periphery of said roll, said contact between said member and said roll being effective to lock said roll against rotation and fixing said cutter in an elevated position for the cutting operation as said ribbon-like material is pulled back against said cutter.

2. In combination, a dispenser body including spaced

coextensive walls adapted to receive a roll of ribbon-like material therebetween, means on said walls of said dispenser body adapted to rotatably mount said roll to enable a user to pull successive lengths of said ribbon-like material from said roll, and a combined cutting and locking member disposed between said walls in spaced confronting relation to the outer periphery of said roll, coaxial pivots on said cutting and locking member intermediate the ends thereof mounting same for rocking movement whereby one end of said member is elevated as the other end of said member is depressed, a cutter formed on said one end of said member and adapted to be engaged by said ribbon-like material as the latter is pulled from said roll, engagement of said ribbon-like material being effective to rock said other end of said member into contact with the outer periphery of said roll, said contact between said member and said roll being effective to lock said roll against rotation and fixing said cutter in an elevated position for the cutting operation as said ribbon-like material is pulled back against said cutter.

3. In combination, a dispenser body including spaced coextensive walls, a roll of ribbon-like material disposed intermediate said walls and journaled on said dispenser body to enable a user to pull successive lengths of said ribbon-like material from said roll, and a combined cutting and locking member disposed between said walls in spaced confronting relation to the outer periphery of said roll, coaxial pivots on said cutting and locking member intermediate the ends thereof mounting same for rocking movement whereby one end of said member is elevated as the other end of said member is depressed, and a cutter formed on said one end of said member and engageable by said ribbon-like material as the latter is pulled from said roll, engagement of said ribbon-like material being effective to rock said other end of said member into contact with the outer periphery of said roll.

4. In a tape dispenser including a rotatably supported roll of tape, the improvement comprising a combined roll locking and tape cutting means including a member disposed at a location adjacent to and spaced from the outer periphery of said roll, means rockably mounting said member intermediate its ends on said tape dispenser, cutting means formed on one end of said member, and locking means formed on the other end of said member, said cutting means rocking into an elevated position relative to said roll when the tape is pulled up into contact with said cutting means and said locking means simultaneously rocking into a depressed position in contact with said roll wherein said roll is locked against rotation during the cutting operation.

5. In a tape dispenser including a dispenser body adapted to rotatably support a roll of tape, combined roll locking and tape cutting means on said dispenser body including a member disposed at a location adjacent to and spaced from the outer periphery of said roll, means mounting said member intermediate its ends on said tape dispenser for rocking movement about a transverse pivot, cutting means formed on said member at one side of said transverse pivot, and locking means formed on said member at the other side of said transverse pivot, said cutting means rocking into an elevated position relative to said roll when the tape is pulled up into contact with said cutting means and said locking means rocking into a depressed position in contact with said roll wherein said roll is locked against rotation during the cutting operation.
